LOCOMOTIVE TENDER

John W. Myers, Roanoke, Va., assignor to The Standard Stoker Company, Incorporated, a corporation of Delaware

Application July 28, 1932, Serial No. 625,279

11 Claims. (Cl. 105—234)

My present invention appertains to locomotive tenders or similar rolling stock of the class equipped with fuel conveying mechanism.

The main object of this invention is the provision of an improved locomotive tender or like carrier of the class described. More specifically the invention resides in the improvement consisting in mounting the motor or prime mover of the conveying mechanism underneath the main underframe and providing extensible and contractible drive means between the motor and the fuel conveyor which is disposed above the underframe in communication with the fuel bunker.

Another object of the invention is to provide a novel mounting arrangement for the motor on the underside of the underframe comprising the formation of a bracket or guideway extending transversely of one longitudinal side portion of the frame for carrying the motor and permitting of its replacement from one side of the tender.

While the aforesaid mounting arrangement may be used with all classes of tenders of the character specified, the other features of my invention are particularly applicable with tenders equipped with stoker conveyors of the movable type. By "movable type", I mean those that are mounted on the tender to swing sidewise, to rock vertically, or to move longitudinally of the tender during normal operation of the locomotive and its tender and stoker device. This form of tender and type of stoker conveyor is illustrated on the drawing, in which,

Figure 1 is a central vertical longitudinal sectional view through the locomotive tender of the invention with some parts shown in section and others in elevation; and

Figure 2 is a transverse sectional view on the line 2—2 of Figure 1.

10 represents the locomotive tender as a whole. It is provided with a "water bottom" main underframe 11 above which is disposed the body portion 12 including the fuel bunker 13 and the water compartment 14. Sloping partition plates as at 15 separate the bunker from the water compartment and are arranged with upstanding plates as at 16 to form a stoker conveyor compartment 17 above the underframe and beneath the fuel bunker. The floor of the conveyor compartment is formed by the imperforate plate portion 18 of the underframe. From this description it will be understood the conveyor compartment is watertight and separated from the water compartment.

A centrally disposed aperture 19 in the floor of the fuel bunker provides communication between the bunker and the conveyor compartment. The

aperture is partially opened or closed by shiftable plates 20 which are of well known construction.

The compartment 17 is of suitable size to receive the movably mounted stoker conveyor indicated as a whole by the numeral 21. This conveyor is of the type that swings sidewise about a vertical axis and rocks vertically about a transversely extending horizontal axis. The specific mounting construction of the conveyor forms no part of my present invention. It is sufficient for purposes of description to point out here that the conveyor swings sidewise about the vertical pivot pin 22 and that it rocks vertically about the transverse foot members 23.

The stoker conveyor is composed of the trough 24 within which is revolvably mounted the conveyor screw 25. A housing 26 at the rearward end of the trough encloses the pinion 27 and the gear 28. The latter is connected in any well known manner, not shown, to the rearward end of the screw 25.

Motion is imparted to the screw through the gearing from the motor or prime mover 30 positioned underneath the main frame 11 at a point rearward of the stoker conveyor. For this purpose the power shaft 31 of the motor carries a universal joint 32 which is connected to the rearward section of the inclined forwardly extending extensible and contractible drive shaft, comprising the telescopic sections 33 and 34, passing through the opening 35 of the underframe to connect with the universal joint 36 carried by the pinion shaft 37. The opening 35 and its extension 35a in the water compartment in effect constitute a rearward and downwardly directed continuation of the conveyor compartment 17. Another opening at 38 is provided in the underframe opposite the housing 26 to provide access thereto. It will be understood the opening 35 is of sufficient size to permit of maximum movement of the telescopic drive shaft due to laterally swinging or other movement of the stoker conveyor.

To facilitate mounting or replacement of the motor 30 a novel securing arrangement is provided and considered an important feature of my invention. This structure consists of a bracket 40 depending from the underside of the main frame 11 and disposed transversely of one longitudinal side portion to open sidewise of the tender at or adjacent a sidewall thereof. The bracket may be fastened to the main frame in any suitable manner or it may be formed integral therewith. Bolts as at 41 hold the motor in a predetermined position on the floor or bottom 42 of the bracket. This bottom or floor serves as a

table or guideway for sliding the motor into position or for withdrawing it therefrom. If desired, the bracket or guideway may be made of a skeleton framework of bars or angles or any other 5 formation that in effect constitutes a guide or guideways for slidably mounting or replacing the motor from a side of the tender where more space is available for such work than directly under the tender.

10. I claim:

1. In a locomotive tender, the combination of a base frame, a body portion above the frame including a fuel bunker, a stoker conveyor movably mounted on the tender in communication with 15 the bunker, a motor mounted below said frame, and an extensible and contractible shaft operatively connecting the motor with the conveyor.

2. In a locomotive tender, the combination of a base frame, a body portion above the frame including a fuel bunker, a stoker trough movably mounted on the tender in communication with the bunker, a conveyor screw in said trough, a housing at the rear of said trough, gearing in said housing connected to said screw, a shaft associated with the gearing and extending rearwardly 25 of the housing, a universal joint carried by said shaft, a motor mounted underneath said frame and having a power shaft, a universal joint carried by the power shaft, and an extensible and 30 contractible drive shaft extending between and being operatively connected to said universal joints for transmitting power from the motor to the gearing.

3. In a locomotive tender, the combination of a base frame, a body portion above the frame including a fuel bunker, a stoker conveyor movably mounted on the tender in communication with the bunker, a motor mounted underneath said frame, and means for transmitting power from 35 the motor to the conveyor including gearing and an extensible and contractible drive shaft universally mounted at its remote ends.

4. In a locomotive tender, the combination of a base frame, a body portion above the frame including a fuel bunker, a stoker conveyor movably mounted on the tender in communication with the bunker, a motor mounted underneath said frame, and means for transmitting power from 45 the motor to the conveyor including an extensible and contractible drive shaft universally mounted at its remote ends.

5. In a locomotive tender, the combination of a base frame, a body portion above the frame including a fuel bunker, a stoker conveyor movably mounted on the tender in communication with the bunker, a motor mounted underneath said frame, and extensible and contractible 55 drive means connecting the motor with the conveyor.

60

6. In a locomotive tender, the combination of a base frame, a body portion above the frame including a fuel bunker, a stoker conveyor movably mounted on the tender in communication with the bunker, a motor positioned underneath said frame, extensible and contractible means connecting the motor with the conveyor, and a bracket depending from the frame for supporting said motor.

7. In a locomotive tender, the combination of a base frame, a body portion above the frame including a fuel bunker, a stoker conveyor movably mounted on the tender in communication with the bunker, a motor positioned underneath said frame, extensible and contractible means connecting the motor with the conveyor, and a bracket depending from the frame for supporting said motor, said bracket extending to one side of the tender forming a guideway for mounting or removing the motor.

8. In a locomotive tender, the combination of a base frame, a body portion above the frame including a fuel bunker, a stoker conveyor in communication with the bunker, a motor positioned underneath said frame, drive means connecting the motor with the conveyor, and a bracket depending from the frame for supporting the motor, said bracket extending to one side of the tender forming a guideway for mounting or removing the motor.

9. In a locomotive tender, the combination of a base frame, a body portion above the frame including a fuel bunker, a stoker conveyor above said frame and in communication with the bunker, the underside of said frame having a guideway 100 formed therewith and extending to a side of the tender, a motor disposed beneath said frame and positioned in the guideway, and drive means connecting the motor with the conveyor.

10. A locomotive tender base frame including 115 a box-like casting having an upper wall and a lower wall, the upper and lower walls of said base frame adjacent the forward end thereof having an aperture therethrough providing access to stoker drive mechanism, said upper and lower 120 wall of said base frame at a point rearward of said named aperture having another aperture extending therethrough for housing a stoker drive shaft.

11. A locomotive tender base frame including 125 a box-like casting having an upper wall and a lower wall, the upper and lower wall having an aperture extending therethrough for housing a stoker drive shaft, said aperture opening through the upper wall of said base frame forward of its 130 opening in the lower wall.
